UNITED STATES PATENT OFFICE.

JOHN BUCKOWITZ, OF ST. LOUIS, MISSOURI.

SURGICAL OR ORTHOPEDIC APPLIANCE.

Application filed February 27, 1926. Serial No. 91,116.

This invention relates to a certain new and useful improvement in surgical or orthopedic appliances.

My invention has for its chief object the provision of a surgical or orthopedic appliance adapted to correct or prevent stiffening deformation of a broken, sprained, or otherwise injured joint, such as the elbow, hip, knee, ankle, and the like.

My invention has for a further object the provision of a surgical or orthopedic appliance of the type and for the purpose stated which is of simple form and construction, which may be economically manufactured, which may be conveniently arranged upon the body in healing or corrective association with the injured joint, and which is usable without undue discomfort.

And with the above and other objects in view, my invention resides in the novel features of form, construction, arrangement, and combination of parts hereinafter described and pointed out in the claims.

In the accompanying drawing,

Figure 1 is an elevational view of a surgical or orthopedic appliance embodying my invention; and

Figures 2, 3, 4 and 5 illustrate the appliance as arranged upon the body in operative healing or correcting association with an injured or deformed elbow, knee, hip, and ankle, respectively.

Referring now more in detail and by reference characters to the drawings, which illustrate a preferred embodiment of my invention, the body A of the appliance is in the form of a suitable elongated brace-strip of preferably rigid metallic material. Provided in the brace-strip A intermediate its ends, as at 1, is an arch or bow of suitable rise. Adjacent its opposite ends, the body or brace A is further provided with pairs of outwardly-presented, oppositely-disposed arms 2—2, each pair of said arms forming a limb engaging yoke. At its one or so-called upper end, the body of the brace A has hinged or pivotally connected thereto, as at 3, a short strip or brace-extension 4, for purposes shortly appearing, the brace A on its under-surface at its opposite ends, the extension 4 on its under-surface at its free end, and the yoke-arms 2 being preferably padded or cushioned, as shown.

Forming part of and completing the appliance, is a sling B comprising a preferably padded seat 5, connected to and at the oppo-

site ends of which are suitable coiled expansive or elastic springs 6—6, which latter, in turn, are connected together in spaced relation at their upper ends by a cross or bridge-piece 7, provided centrally with an eye 8 with which connectingly or suspendingly engages a turn-buckle or other suitable carrier 9 depending from the crown of the arch or bow 1 of the brace A.

In use, and first when employed in connection with an injured or deformed elbow, as illustrated in Figure 2, the brace A is fitted at its yokes 2 in engagement upon the forearm and shoulder-portion or arm proper 70 of the arm C, the extension 4 being disposed in brace-supporting position upon the breast and the bow or arch 1 being disposed over the elbow. The sling B is then suitably engaged with the arm, with its seat 5 disposed under the elbow, as shown.

When employed in connection with an injured or broken knee, as illustrated in Figure 3, the brace-extension 4 is pivotally swung to align with the brace A, and the brace A then fitted lengthwise under the leg D and engaged at its yokes 2 with the calf and thigh. The sling B is then fitted upon the leg and its seat 5 engaged with and upon the knee, as shown.

When employed in connection with an injured or deformed hip E, as illustrated in Figure 4, the brace A is engaged at its yokes 2 both above and below the hip and forwardly of the body, with the bow 1 disposed over the hip. The sling B is then fitted upon the leg and its seat 5 disposed under the hip, as shown, the strip 4 being dispensed with or disposed in alignment with the strip A, as in Figure 3.

When employed in connection with an injured or deformed ankle F, as illustrated in Figure 5 the brace A is fitted upon and engaged at its yokes 2 with the leg at the ankle, with its bow 1 disposed approximately 100 directly over the ankle, the extension 4 being also dispensed with or disposed in alignment with the strip A, as in Figure 3. The sling B is then suitably disposed upon the leg and its seat 5 engaged under the heel, as shown.

In each instance or application, the tension of the springs 6 is conveniently adjusted by means of the turn-buckle 9, as may be required by the conditions of the particular case, the appliance functioning through the yielding engagement provided by the springs 6 between the sling-member 5 and the par-

ticular injured joint to exert a resilient pull or pressure upon the injured joint tending constantly to yieldingly straighten the injured or deformed limb.

5 My new appliance may be economically manufactured, is easily and conveniently applied in connection with the injured or deformed limb and joint, and from use has been found exceedingly efficient in the performance of its intended function.

It will be understood that my appliance, including its several parts, may be of different sizes, and that changes in the form, construction, arrangement, and combination of the several parts thereof may be made and substituted for those herein shown and described without departing from the nature and principle of my invention.

15 Having thus described my invention, what 20 I claim and desire to secure by Letters Patent is:

1. A surgical or orthopedic appliance including a rigid brace bowed intermediate its ends, adapted for application upon the

body in operative location relatively to a 25 limb and a joint thereof, and a sling comprising a turn-buckle connected at an end to the brace at the crown of its bow, a pair of spaced elastic springs having connection at an end with the free end of the turn-buckle, and a seat having connection with the free ends of the springs and adapted for engagement with the limb at said joint.

30 2. A surgical or orthopedic appliance including a rigid brace bowed intermediate 35 its ends, adapted for application upon the body in operative location relatively to a limb and a joint thereof, and a sling comprising a carrier connected at an end to the brace at the crown of its bow, a pair of 40 spaced elastic springs having connection at an end with the free end of the carrier, and a seat having connection with the free ends of the springs and adapted for engagement with the limb at said joint.

45 In testimony whereof I have affixed my signature.

JOHN BUCKOWITZ.
